COMBINED BED AND TABLE UNIT

Chester A. Pink, Highland Park, Ill., assignor to The
Englander Company, Inc., a corporation of New York

Continuation of design application Ser. No. 64,993, May
1, 1961. This application Nov. 19, 1964, Ser. No.
82,702

The portion of the term of the patent subsequent to
Sept. 25, 1979, has been disclaimed

Term of patent 14 years

(Cl. D5—4)

FIG. 1 is a perspective view showing a combined bed and table unit embodying my design;

FIG. 2 is another perspective view of the combined bed and table unit embodying my design; and

FIG. 3 is an end elevational view showing the combined bed and table unit embodying my design.

The dominant features of my design reside in those portions shown in full lines on the drawing. The back of the combined bed and table unit is of conventional configuration.

This application is a continuation of my earlier filed application Serial No. D. 64,993, filed May 1, 1961, and now abandoned.

I claim:

The ornamental design for a combined bed and table unit, substantially as shown and described.
